UNITED STATES PATENT OFFICE.

GEORGE HENRY EVANS, OF MEMPHIS, TENNESSEE.

LAND-ANCHOR.

1,108,158.

Specification of Letters Patent. Patented Aug. 25, 1914.

Application filed January 23, 1914. Serial No. 813,947.

To all whom it may concern:

Be it known that I, GEORGE HENRY EVANS, a citizen of the United States, residing at Memphis, in the county of Shelby and State 5 of Tennessee, have invented certain new and useful Improvements in Land-Anchors, of which the following is a specification, reference being had to the accompanying drawings.

10 This invention relates to certain improvements in land anchors and the object of the invention is to provide a device of this general character which may be assembled with convenience and facility and when in applied position will effectively withstand all 15 strain that may be imposed thereupon.

The invention consists in the details of construction and in the combination and arrangement of the several parts of my improved land anchor whereby certain important advantages are attained and the device is rendered simpler, less expensive and otherwise more convenient and advantageous for 25 use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a transverse sectional view taken through a land anchor constructed in accordance with an embodiment of my invention, such anchor being shown in operative position; Fig. 2 is substantially a central longitudinal section of the device as illustrated in Fig. 1; and Fig. 3 is a fragmentary view in elevation of the engaging 40 end of the rod included in my invention, as herein set forth.

As disclosed in the accompanying drawings, 1 denotes a pit in which my improved anchor is adapted to be positioned, the bottom of such pit being provided, at substantially its transverse center, with a recess 2 which is adapted to accommodate the beam 3, comprised in my invention, which is substantially circular in cross section and 45 adapted to be freely movable in a lateral direction. Suitably secured to the beam 3, at substantially the center thereof, is the up-standing rod 4 terminating in a hook member 5 which is adapted to afford a suitable 50 engaging means whereby a guy or other brace member may be suitably connected.

Coacting with the beam 3 are the flat members or boards 6 which are adapted to bear against the sides of the pit 1 and have suitably secured thereto at an angle the arms 60 7 of predetermined length, the lower or free ends of which are adapted to bear against the periphery of the beam whereby it will be seen that the members 6 will automatically adjust themselves to the pit in which my improved anchor may be applied; and it will also be obvious that should for any reason such walls give way the tendency of the members 6, under the action of the strain imposed thereupon by the guy or brace, will result in such parts automatically compensating for any differences in width of the pit that may result. This particular advantage is created by having the lower ends 70 of the arms 7 in free contact with the periphery of the beam, as is believed to be clearly apparent and it will be further observed that the arm 7 of one member 6 is offset relative to the arm 7 of the second member 6 so that no obstruction will be 75 offered to the movement of said member 6 either in unison or one independently of the other. After my improved anchor is assembled within the pit, I find it of advantage to position on the walls of the pit the peg members 8 or the like, such pegs 8 being in substantial contact with the upper longitudinal edges of the members 6, whereby it will be seen that the same are effectively maintained against any possible upward movement. It 80 will also be obvious that by having the beam 3 capable of free axial rotation, the rod 4 will readily accommodate itself to the proper angle of strain imposed thereupon. It is to be observed that the ends of the arms 7 85 are adapted to contact with the beam 3 are recessed, as is shown at 8 in Fig. 1.

From the foregoing description, it is thought to be obvious that a land anchor constructed in accordance with an embodiment of my invention is of an extremely 100 simple and comparatively inexpensive nature and is particularly well adapted for use by reason of the convenience and facility with which it may be assembled and the certainty with which it performs its functions and it will also be obvious that my invention is susceptible of some change and modification without material departure from the principles and spirit thereof and for this 105 reason I do not wish to be understood as limiting myself to the precise arrangement and

formation of the several parts herein shown in carrying out my invention in practice.

I claim:

1. A land anchor of the character described comprising an elongated beam substantially circular in cross section, elongated flat members, spaced parallel flat arms projecting from the members on an incline disposed transversely of the members, the free extremities of said arms being adapted to freely contact with the periphery of the beam, and a rod projecting from the beam at a point intermediate the engagement of the arms with the beam.
- 10 2. A land anchor of the character described comprising an elongated beam substantially circular in cross section, elongated

flat members, spaced parallel flat arms projecting from the members on an incline disposed transversely of the members, the free 20 extremities of said arms being adapted to freely contact with the periphery of the beam, and a rod projecting from the beam at a point intermediate of the engagement of the arms with the beam, the ends of the arms 25 adapted to contact with the beam being recessed.

In testimony whereof I hereunto affix my signature in the presence of two witnesses.

GEORGE HENRY EVANS.
